CONTROL DEVICE

Claude A. Nelson, Wilmerding, Pa., assignor to
 The Westinghouse Air Brake Company, Wil-
 merding, Pa., a corporation of Pennsylvania

Application August 31, 1944, Serial No. 552,024

2 Claims. (Cl. 121—41)

1

This invention relates to control devices and more particularly to fluid pressure controlled and operated motors.

One object of the invention is the provision of an improved motor of the above type.

Fluid motors employed on airplanes for adjusting various devices such as engine throttles, mixture control devices etc. must be as small, compact and light in weight as possible, and another object of the invention is the provision of an improved fluid motor embodying these characteristics and therefore particularly adapted, though not limited, for such use.

The fluid motor embodying the invention comprises a power member which may be in the form of a piston and which is adapted to be operated by fluid under pressure to effect adjustment of the device to which it may be operatively connected, and a pilot portion arranged for control by fluid under pressure to control the pressure of fluid on the power piston, and according to another feature of the invention a single pipe is employed for controlling the pilot portion of the motor and for supplying fluid under pressure to the motor for actuating the power piston, thereby maintaining at a minimum the weight of the system for controlling the motor.

Other objects and advantages will be apparent from the following more detailed description of the invention.

In the accompanying drawing, the single figure is a longitudinal sectional view of a fluid motor embodying the invention.

Description

The improved fluid motor comprises a casing made up of sections 1, 2, and 3 which are adapted to be rigidly secured together in the relationship in which they are shown in the drawing. A flexible diaphragm 4 is clamped around its edge between the casing sections 1 and 2, while a flexible diaphragm 5 is clamped around its edge between the casing sections 2 and 3, said diaphragms being of the same areas and arranged in coaxial relation.

Between the two diaphragms 4 and 5 is a chamber 6 containing a strut 7 having at one end a head 8 engaging the adjacent face of diaphragm 4, and having at the opposite end a head 9 engaging the adjacent face of diaphragm 5. At the opposite side of diaphragm 4 is a control chamber 10 connected through a passage 10a to a combined, or common control and fluid pressure supply pipe 11. Chamber 10 contains a follower 12 engaging the adjacent face of diaphragm

4 opposite the strut head 8. At the opposite or right hand side of diaphragm 5, as viewed in the drawing, is a chamber 13 which is open to atmosphere through a port 14 and which contains a follower 15 engaging the adjacent face of said diaphragm. The strut heads 8 and 9 and oppositely arranged followers 12 and 15 are secured to the respective diaphragms by any suitable means or in any suitable manner, not shown in the drawing.

2

15 A bore is provided centrally through the strut head 8, follower 12 and the interposed portion of diaphragm 4, and slidably mounted in this bore is a fluted stem 16. A fluid pressure supply valve 17 disposed in chamber 10 is provided on one end of the stem 16, while on the opposite end of said stem, which terminates in chamber 6, there is provided a fluid pressure release valve 18. The follower 12 has a seat for engagement by the supply valve 17, while a seat for the release valve 18 is provided on an arm 19, the seat extending around one end of a bore 20 in said arm. The arm 19 is an integral part of the casing section 2 and extends into the space between the two strut heads 8 and 9. The opposite end of bore 20 opens to a chamber 21 in arm 19 and said chamber is connected by a passage 22 to a fluid release pipe 23.

20 The fluid release pipe 23 may lead directly to atmosphere, or it may be connected to a sump reservoir (not shown) employed for receiving fluid under pressure after it has been used to produce a desired operation. Fluid under pressure thus released to the sump reservoir will then be recompressed into a storage reservoir for use again. Particularly on large airplanes where many fluid motors will be used for controlling different devices, pressure of fluid in the sump reservoir may vary from, for instance, atmospheric pressure when no fluid pressure is being released to the reservoir, to, momentarily, a relatively high degree, such as thirty-five pounds, if fluid under pressure is released to said reservoir from all of the controlling motors at the same time. In the present application it is merely desired to bring out however that, in practice, the pressure of fluid in pipe 23 and thus in chamber 21 acting on the seating side of the release valve 18 may be of any degree between atmospheric and 25 a certain higher pressure, such as thirty-five pounds, as just described. No further description of the sump reservoir or its function is essential in the present application, although if desired, reference may be made to the copending application of Rankin J. Bush, Serial No. 480,161,

filed March 23, 1943, and assigned to the assignee of the present application, which discloses a control system embodying a sump reservoir, such as above referred to.

A bore is provided through the casing section 1 in coaxial relation to the supply valve 17, and secured to said casing section over the outer end of said bore is a hollow cap 24. Slidably mounted in this bore is a sleeve 25 extending into control chamber 10 and having a closed end which engages the supply valve 17. A coil spring 26 mounted in sleeve 25 and having one end bearing against the closed end of said sleeve, extends into cap 24. The opposite end of spring 26 bears against cap 24. This spring is under pressure and acts on the supply valve 17 with only sufficient force to ensure seating of said valve against the follower plate 12 or seating of the release valve 18 against its seat.

Within the cap 24, the sleeve 25 is provided with an annular collar 27 for contact with the casing section 1 when said casing section is removed from the section 2, so as to hold the spring 26 and sleeve 25 assembled within the casing section 1, under such a condition.

The casing section 3 has a bore 28 formed in coaxial relation with the diaphragms 4 and 5 and containing a power movable abutment which may be in the form of a piston 29. The chamber 13 is provided at one side of piston 29 whereby said piston is constantly subject on this one side to atmospheric pressure. At the opposite side of piston 29 is a power or operating pressure chamber 30 which is in constant communication through passage 31 with chamber 6 formed between the two diaphragms 4 and 5.

The piston 29 has a stem 32 extending through chamber 30 and a bore in the casing section 3 to the exterior thereof. A resilient ring 33 carried in an annular groove in casing section 3 has sealing and sliding contact with the portion of the piston stem within the bore in said casing section to prevent leakage of fluid under pressure from chamber 30 around said stem to atmosphere.

The outer end of the piston stem 32 is connected by a pin 34 to a lever 35 at a point between the ends of said lever. One end of lever 35 is connected by a pin 36 to a fulcrum link 37 mounted to turn on a pin 37a carried in the casing section 3. In the opposite end of lever 35 is a hole 38 for receiving a pin (not shown) to connect said lever, and thereby the power piston 29, to a device which it is desired to operate.

In chamber 13 are two concentrically arranged coil springs 39 and 40 both of which bear at one end against the piston 29. The opposite end of spring 39 is supported on a shelf 41 projecting from casing section 3 into chamber 13. The opposite end of spring 40, which may be called a regulating spring, bears against the diaphragm follower 15.

As above mentioned, pipe 11 constitutes a combined control and fluid pressure supply pipe, that is to say constitutes a control pipe for controlling operation of the diaphragms 4 and 5 and thereby the supply valve 17 and release valve 18, which parts constitute a pilot portion of the motor, and also constitutes a fluid pressure supply pipe, or a source of fluid under pressure, from which fluid under pressure is obtained for controlling operation of the power piston 29, in a manner which will be later described. Due to pipe 11 constituting a source of fluid under pressure as just mentioned, the normal or minimum pressure in said

pipe will preferably be in excess of atmospheric pressure, for example it may be fifty pounds.

The spring 40 is interposed between the diaphragm follower 15 and power piston 29 under such a degree of pressure that, with the piston 29 in a normal position defined by contact with a stop 42 in casing section 3, the pressure of said spring on the diaphragm follower 15 will hold the diaphragms 4 and 5 against the opposing control pipe pressure (50 pounds) in chamber 10 in a position in which the supply valve 17 will be seated and the release valve 18 will also be seated or slightly open.

The spring 40 is connected to the power piston 29 to render said piston effective to control, through said spring, certain operation of the diaphragms 4 and 5 and valves 17 and 18, as will be later described, but it will be noted that said spring is also effective to urge piston 29 in the direction of stop 42. The spring 39 is confined under pressure between the shelf 41 and piston 29 and its sole function is to urge the piston 29 into contact with stop 42 upon reducing pressure of fluid in chamber 30, as will be later described.

It will be understood that the spring 39 is required to coact with spring 40 to move piston 29 in the direction of and into contact with stop 42 only in case the resistance to such movement exceeds the pressure of spring 40, as may be the case where piston 29 is of relatively large area, or where a relatively great force is required to operate lever 35 and the device which may be connected to said lever. If the force opposing movement of piston 29 in the direction of stop 42 were sufficiently great, the pressure of spring 40 on said piston might be of negligible value in obtaining such movement. However, if the force opposing movement of piston 29 in the direction of and into contact with stop 42 does not exceed the force of spring 40, then the spring 39 might be dispensed with.

The area of piston 29 is such as to render it effective to rock lever 35 to operate the connected device (not shown) against the opposing pressure of spring 40 or of both springs 39 and 40 by a lower pressure of fluid in chamber 30 than is required in chamber 10 on diaphragm 4 to move said diaphragm, the strut 7 and diaphragm 5 against spring 40. The diameter of piston 29 will therefore depend upon the load which it is required to operate and may be even greater than shown in the drawing.

Operation

Let it initially be assumed that the control pipe 11 and control chamber 10 are charged with fluid at the minimum pressure of fifty pounds above mentioned. Under this condition, the parts of the motor will assume the positions in which they are shown in the drawing, as will be apparent from the foregoing description.

If the pressure of fluid in pipe 11 and in chamber 10 is now increased, this increased pressure effective on diaphragm 4 will overcome the opposing force of control spring 40 and move the diaphragms 4, 5 and strut 7, and followers 12 and 15 and the adjacent end of said spring in unison against the opposing force of said spring and relative to the opposite end of said spring and piston 29. If the release valve 18 is not seated when the pressure in chamber 10 is at the normal degree, the initial deflection of the diaphragms will permit seating of said valve under the action of spring 25. With the release valve 18 seated, however, said valve will hold the supply valve 17

against movement with the diaphragms, so that upon further deflection of the diaphragms the seat for said supply valve on follower 12 will be moved away from the supply valve.

Upon opening of the supply valve 17 as just described, fluid under pressure supplied to chamber 10 from the control pipe 11, which pipe constitutes a supply source of fluid under pressure, will then flow past the supply valve to chamber 6 and thence through passage 31 to chamber 30.

When the pressure of fluid supplied to chamber 30, and acting on piston 29 is then increased to a degree sufficient to overcome spring 40 or of both springs 39 and 40, as the case may be, and to also actuate lever 35 to operate the device being controlled, said piston will move against the opposing force of said spring or springs, and such movement will act to increase the force of spring 40 opposing the pressure of fluid in chamber 10 on diaphragm 4.

Now assuming that the increase in pressure of fluid in chamber 10, effective on diaphragm 4, is limited to some degree lower than maximum pressure, then when the pressure of spring 40 is increased, by movement of piston 29, to a degree sufficient to overcome the opposing force of said pressure of fluid in chamber 10, said spring will be operated by said piston to move the diaphragms and followers in the direction of the open supply valve 17 and finally move the follower 12 into seating engagement with said valve. When the supply valve is thus closed, further flow of fluid under pressure will be prevented to chamber 30 and, as a result, movement of the piston 29 will cease. When the piston 29 stops moving, the spring 40 becomes static and movement of the diaphragms will also cease in a position in which the release valve will be still seated, whereby the fluid under pressure will be bottled in chamber 30 to maintain the piston 29 and lever 35 against movement.

From the above description it will be noted that the power piston 29 moves to a position determined by and corresponding to the degree of increase in pressure of fluid in chamber 10 above the normal or minimum pressure, and it will be further noted that this movement of the power piston, while opposed by springs 39 and 40, is dependent upon a sufficient increase in pressure in chamber 30 to actuate the lever 35 and the device which may be connected to said lever. Thus a relatively low pressure of fluid in chamber 30 may be adequate to operate the piston 29 at one time or under a certain condition, while a higher pressure of fluid will be required to cause the same movement of said piston at another time or under a different condition. The area of piston 29 is such however that under all conditions it will be moved against spring 40, by fluid in chamber 30 at a lower pressure than is present in chamber 10, and in pipe 11 which constitutes the source of supply of fluid under pressure for operating said piston.

Now let it be assumed that the pressure of fluid in chamber 10 is increased to a higher degree than above considered. Upon such an increase the diaphragms 4, 5 will again be deflected against the opposing force of spring 40 to reopen the supply valve 17 for supplying more fluid under pressure to chamber 30. The piston 29 will then again move against the opposing force of spring 40 or of springs 39 and 40 and cause operation of the diaphragms to again close the supply valve in a new position of said piston, corresponding again to the increase in pressure fluid in

chamber 10, as will be evident from the above description.

In the operation just described, the piston 29, due to the action of spring 40, may or may not move in unison with the diaphragms 4, 5 as they are operated to open the supply valve 17, depending upon the resistance to movement of the device (not shown) which is operated by lever 35. If this resistance is sufficiently great the piston 29 may remain stationary when the diaphragms 4, 5 operate to open the supply valve 17, but if sufficiently small, said piston may move with said diaphragm to open the supply valve. If the piston 29 does not move with the diaphragms 4, 5 to open the supply valve 17, it will be immaterial however, since as little as one one-thousandth of an inch movement will open said valve to supply fluid under pressure to chamber 30 to stop such movement of said piston. Moreover, this small amount of movement of piston 29 would have substantially no effect upon the device connected to lever 35, and said piston will be promptly operated by the fluid under pressure supplied to chamber 30 to the position corresponding to the increase in pressure in chamber 10, as above described.

It will now be seen that the piston 29 can be caused to move from the normal position, in which it is shown in the drawing, to any selected position at the left hand side of normal position by providing the proper pressure of fluid in chamber 10 in excess of the normal or minimum pressure.

With the piston 29 moved away from stop 42, due to the pressure of fluid in chamber 10 having been increased as above described, let it be assumed that it is desired to move said piston back in the direction of said stop. To accomplish this, the pressure of fluid in chamber 10 will be reduced to destroy the equilibrium between its effect on diaphragm 4 and the opposing pressure of spring 40. Spring 40 will then deflect the diaphragms in the direction of chamber 10. This movement of the diaphragms and thereby of the seated supply valve 17 will act through the stem 16 to pull the release valve 18 out of contact with its seat, whereupon fluid under pressure will be released from chamber 30 through passage 31, chamber 6 and past said release valve to chamber 21 and thence through passage 22 to release pipe 23. The consequent reduction in the pressure of fluid in chamber 30 will then permit movement of piston 29 by spring 40 or springs 39 and 40 in the direction of stop 42, it being noted that such movement will allow expansion of spring 40 and thus a reduction in the force it exerts against the diaphragms.

Assuming that the pressure of fluid in chamber 10 is not reduced to its normal degree, then as soon as the pressure of spring 40 becomes reduced, as just described, to a degree which substantially equals the force on diaphragm 4 provided by the pressure of fluid in chamber 10, the diaphragms and valves will be moved in unison by pressure of fluid in said chamber and cause the release valve 18 to move toward its seat and finally into contact with its seat in a position of piston 29 in which the reduced pressure of spring 40 substantially equals the force developed by the reduced pressure of fluid in chamber 10 acting on the diaphragm 4. When the release valve is thus closed further release of fluid under pressure from chamber 30 will stop and piston 29 will then stop moving in a position corresponding to the degree of reduction in pressure of fluid in

chamber 10, or in other words, corresponding to the pressure in said chamber in excess of the normal minimum pressure.

In the operation just described, the piston 29 may, or may not, move in unison with diaphragms 4 and 5 in response to a reduction in pressure of fluid in chamber 10, depending upon the resistance to movement of the device (not shown) connected to lever 35, as will be obvious from the above description of operation of the device in response to an increase in pressure of fluid in chamber 10. Regardless of this, however, the piston 29 will be moved to a position corresponding to the pressure of fluid in chamber 10 upon a reduction in such pressure, as above described.

Upon a further reduction in pressure of fluid in chamber 10, the motor will again operate, as just described, to cause a corresponding change in position of piston 29. If the pressure of fluid in chamber 10 is reduced to the normal degree, the piston 29 will be moved by spring 39 or springs 39 and 40 to its normal position in which it is shown in the drawing. Before the release valve 18 seats or it may seat at the instant said piston engages stop 42. In either case, a complete return of the piston 29 to its normal position will be obtained.

If as just mentioned the release valve 18 is seated at the time piston 29 contacts stop 42, the pilot diaphragm 4 will be conditioned to operate to more quickly open the supply valve 17 upon a subsequent increase in pressure in chamber 10, also, the closing of said valve at this time may bottle up fluid in said chamber at a pressure insufficient however to move piston 29 out of contact with said stop. This bottled pressure however will render piston 29 more quickly responsive to a subsequent supply of fluid under pressure to said chamber by opening of the supply valve 17, as will be readily apparent.

It will now be seen that the power piston 29 can be caused to move toward and to be stopped in any selected position out of its normal position by reducing the pressure fluid in chamber 10 to the proper selected degree, or the full and uninterrupted return to normal position may be obtained, if desired, by a continuous reduction in pressure of fluid in chamber 10 to the normal minimum pressure.

It will be noted that the pressure of fluid in chamber 30 also acts in chamber 6 at all times but has substantially no influence upon the above described operation of the pilot portion of the motor due to its action on one diaphragm being counteracted by its effect on the other diaphragm.

In case pipe 23 is connected to a sump reservoir, as hereinbefore mentioned, it will be seen that the pressure of fluid in chamber 30 can only be reduced as above described, to the pressure effective in said reservoir. The pressure of springs 39 and 40 is such however as to insure movement of the piston 29 into contact with stop 42 against the maximum pressure which may be effective in the sump reservoir and in chamber 30.

Summary

It will now be apparent that I have provided a power motor which is relatively simple and compact and which may be relatively small and light in weight, for the purpose intended. The motor comprises a power portion which is operable by fluid under pressure, and a fluid pres-

sure controlled pilot portion for controlling the power portion, and a single or common pipe serves as a control pipe for the pilot portion and as a fluid pressure supply pipe, or as a source of fluid under pressure, for controlling operation of the power portion.

Having now described my invention, what I claim as and desire to secure by Letters Patent, is:

1. A fluid motor comprising a casing, power means in said casing subject on one side to pressure of fluid in a power chamber, pilot means in said casing arranged in coaxial relation to said power means and subject on the opposite side to pressure of fluid in a control chamber connected to a fluid pressure supply and control passage, a coil spring in said casing acting on adjacent sides of said power and pilot means in opposition to pressure of fluid in the respective said chambers, valve means controlled by said pilot means for controlling communication between said passage and a third chamber at the opposite side of said pilot means, means opening said third chamber to said power chamber, said valve means also controlling a communication between said third chamber, and thereby said power chamber, and atmosphere, said pilot means being operable upon an increase in pressure of fluid in said control chamber to effect operation of said valve means to open communication between said passage and said third chamber and being operable upon a reduction of pressure of fluid in said control chamber to open said third chamber to atmosphere, and means in said casing counteracting the action of fluid pressure in the said third chamber on said pilot means and rendering the adjacent side of said power means subject to atmospheric pressure.

2. A fluid motor comprising a casing, power means in said casing subject on one side to pressure of fluid in a power chamber, pilot means in said casing arranged in coaxial relation to said power means and subject on the opposite side to pressure of fluid in a control chamber, a coil spring in said casing acting against adjacent sides of said power and pilot means in opposition to pressure of fluid in the respective said chambers, valve means in said casing controlled by said power and pilot means and operable by said pilot means upon an increase in pressure of fluid in said control chamber to supply fluid to a third chamber at the opposite side of said pilot means and operable upon a reduction in pressure of fluid in said control chamber to release fluid under pressure from said third chamber, means providing a constantly open communication between said third chamber and said power chamber, said power means being operable either against or by said spring means, to a position corresponding to the increase or reduction in pressure of fluid in said control chamber, to effect operation of said valve means to bottle the fluid pressure in said third and power chambers, the pressure of fluid in said third chamber being effective on said pilot means in opposition to pressure of fluid in said control chamber, and means operable by pressure of fluid in said third chamber to counteract the effect of the pressure of fluid in said third chamber on said pilot means and also rendering the adjacent side of said power means subject to atmospheric pressure.
